UNITED STATES PATENT OFFICE.

HANNIBAL ALEXANDER KUNITZ, OF SPRINGFIELD, MASSACHUSETTS, ASSIGNOR TO GILBERT & BARKER MANUFACTURING COMPANY, OF WEST SPRINGFIELD, MASSACHUSETTS, A CORPORATION OF MASSACHUSETTS.

BURNER.

1,374,153.

Specification of Letters Patent.

Patented Apr. 5, 1921.

Application filed January 8, 1920. Serial No. 350,154.

To all whom it may concern:

Be it known that I, HANNIBAL A. KUNITZ, born in Tunis, of a German father and French mother, and not positively knowing 5 of what citizenship I am, but having formally declared my intention of becoming a citizen of the United States, in accordance with the United States naturalization laws, and having diligently prosecuted my application for United States citizenship to date, 10 and now residing at Springfield, in the county of Hampden and State of Massachusetts, United States of America, have invented certain new and useful Improvements 15 in Burners, of which the following is a specification.

This invention relates to improvements in burners, and, more particularly, to that class 20 of burners wherein the atomization of fuel occurs outside the burner itself. While the invention is capable of general application, it finds one advantageous use as a burner for liquid fuel, such as oil, which is atomized by mingling with a suitable fluid, such as 25 steam or air, for example.

The object of the invention is to provide a burner built up of two members, such as a body and cap, with removable plates therebetween which coöperate with each other 30 and the cap and body to form the nozzles of the burner.

According to this object, the removable plates control the thickness and width of the nozzles as well as the angle of the mouth 35 of the nozzle, while the body and cap have no effect on the characteristics of the nozzles. Thus, the body and cap may be stand- 40 ardized and used under all conditions while the removable plates may be changed or other plates substituted, to provide just the desired characteristics to meet the varying conditions of each burner installation, as encountered.

Another object of the invention is to pro- 45 vide a burner, comprising, a body and cap between which may be clamped a plurality of plates so arranged as to provide a plurality of nozzles for fuel and the atomizing medium.

Another object of the invention is to pro- 50 vide a burner made up of thin plates or laminations, which are clamped between a cap and body, and to build up the burner by the use of a series of each of two types of

laminations. One series consists of nozzle 55 forming members and the other of blank laminations and the blanks and nozzle forming laminations are alternated to form the burner.

Another object of the invention is to pro- 60 vide, in a burner of the type described, pas- sages for the fuel and atomizing medium and a series of similar nozzle plates, each nozzle plate being reversible and having a recess which may register with either of 65 said passages, but not with both.

Other objects and advantages will appear in the following description and in the illus- 70 trative embodiment of the invention in the accompanying drawings, in which:

Figure 1 is a top plan view of a burner embodying the invention;

Fig. 2 is a front elevational view thereof;

Fig. 3 is a sectional plan view taken on the line 3—3 of Fig. 2; and 75

Figs. 4 and 5 are plan views showing the nozzle forming and blank plates or lami- 75 nations, respectively of the burner.

Referring to these drawings; the burner comprises a body 10, a cap 11, a series of 80 removable plates or laminations between the cap and body, and suitable means, as bolts 12 for example, for removably securing these members together. The cap and body may be formed as desired. The cap 11 has no 85 passages other than those for the retaining bolts 12 and requires no special description. The body 10, however, has two passages 13 and 14, in addition to those for bolts 12, which constitute the inlets for fuel, such as 90 oil for example, and the atomizing medium, such as steam or air for example. The pas- 95 sages 13 and 14 lead to the top face 15 of body 10 and the faces 15 and 16 are flat plane surfaces, between which the removable 95 plates or laminations are clamped. It is not important which of the passages 13 and 14 is selected for the fuel passage, but for the purposes of description the passage 13 will be assumed to be the inlet for the atomiz- 100 ing fluid, and the passage 14 the inlet for the fuel.

The laminations or plates are of two types,—nozzle-forming plates 17 (Fig. 4) and blank plates 18 (Fig. 5). Both types 105 of plates are preferably, although not neces- sarily, of the same size and shape as the face 15 of body 10. Both plates have holes

19 therethrough to register with the bolt holes in the cap and body and to receive the bolts 12. Aside from such holes the blank plate 18 has two holes 20 and 21 therethrough which are so located as to register with the inlet passages 13 and 14, the plate being reversible so that either of the holes may register with either of the passages.

10 The nozzle-forming plate 17, however, has but a single hole 22 therethrough and such hole is so located that it can register with either of the inlet passages 13 or 14 according to which of its faces is uppermost. The plate 17 is also provided with a recess 23 15 therethrough, which extends from the front edge of the plate inwardly to a position such that it may communicate with either of the inlet passages 13 or 14 according to which face is uppermost. The plate 17 is made 20 reversible by locating the outer or nozzle end of recess 23 centrally between the two outer bolt holes 19 and centrally between the hole 22 and the inner portion of the recess, the remaining portion of the recess diverging 25 to connect these two portions. The two outer bolts 19 thus function as means for locating the plates relatively to the cap and body and while they also have a function as retaining means, the first function is the 30 important one for the retaining may be otherwise provided for if desired.

While preferably the nozzle-forming plates 17 are made reversible, since the one plate can then serve as the nozzle-forming 35 member for either the fuel or the atomizing fluid, the invention, as to certain features, is independent of this arrangement. For example, it is sometimes desired to have one nozzle wider than the other and possibly 40 of somewhat different shape. Thus, as indicated in Figs. 1 and 2, the nozzle exit 24 of the lower plate 17, which exit is intended for steam, may be somewhat smaller than the nozzle exit 25 of the plate 17 next 45 above it, which exit is intended for fuel. Under such conditions the reversibility of the nozzle-forming plates is not so important although it is nevertheless desirable.

In assembling the burner, a plate 17 is 50 slipped over the bolts 12 and laid upon the face 15 of the burner with the inner end of its recess 23 communicating with one of the inlet passages,—for example the passage 13. The hole 22 in such plate then registers with the other passage, as 14. Then a blank plate 18 is applied on top of the plate 17 55 and its holes 20 and 21 line up with the holes 13 and 14, so as to permit passages of fuel and atomizing fluid therethrough. 60 A second plate 17 is then applied, but reversely of the first plate 17, so that the inner end of its recess 23 communicates with the passage 14 and the hole 22 registers with the passage 13. If only two nozzles,—one 65 for fuel and one for atomizing fluid,—are

desired, the cap 11 is then applied, which blanks off both the recess 23 and hole 22 in the plate. If other nozzles are desired, as illustrated, a second blank plate 18 is applied and the described operations are repeated.

The operation of the burner will now be described assuming that fuel, as oil, is supplied to the passage 14 and an atomizing medium, as steam, is supplied to the passage 75 13. The fuel travels upwardly from the passage 14 and through the hole 22 in the lower plate 17, the hole 21 in the blank plate 18, and thence into the recess 23. This recess is closed off from above and below by 80 the adjacent blank plates 18 so that a passage is provided through which the fuel may pass to and be emitted from the front of the burner. In case a second fuel nozzle is provided, some of the fuel will continue 85 on through the second blank plate 18, the third plate 17 and the third blank plate 18 into the recess 23 of the upper plate 17 which recess is closed at the bottom by the third blank plate 18 and at the top by the 90 cap 11, or another blank plate if desired. The steam passes upwardly into the recess 23 of the first plate 17 and also continues upwardly through the first blank plate 18, the second plate 17, and the second blank 95 plate into the recess 23 of the third plate 17. The fuel and the atomizing medium travel outwardly through their respective recesses 23 and are emitted in parallel planes, the fuel jet being preferably disposed above the 100 jet of atomizing fluid so that the former falls into the latter and is atomized thereby.

An important feature of the described construction is that the cap and body,—the relatively expensive elements of the 105 burner,—may be standardized. That is, only one style of cap and body need be manufactured and the varying conditions of each installation may be met by varying the plates, which are relatively inexpensive to 110 manufacture and may readily be produced by punching operations, if desired. With only the two types of plates illustrated, a burner having as many jets as desired may be produced and the relative arrangement of these 115 jets may be varied as desired. One is not limited to the alternate arrangement of fuel and steam jets described, but can readily provide more jets for fuel than for steam or vice versa or can arrange the steam jets 120 above the fuel jets, if desired. The construction described is therefore flexible to meet a wide range of varying conditions.

Furthermore, the manufacturer may readily provide plates of various thicknesses so 125 that by substituting one for another the height of the nozzle opening may be varied. The spacing of adjacent jets may be similarly controlled. Moreover, plates having recesses 23 of different widths and even dif- 130

ferent shapes may be provided. In short, by the described construction, the vital characteristics of the nozzles are controlled by the relatively inexpensive and removable plates and may be readily varied as desired by using various plates.

The plates being removable, are consequently renewable when they become worn, as by the cutting action of the steam for example. The inner and vital parts of the burner are readily accessible for inspection or cleaning and access to the interior of the burner may be had without disturbing the piping, since there are no pipe connections to the cap 11, the inlets for both fuel and the atomizing medium being in the body, which is considered important.

The invention has been disclosed herein, in an embodiment at present preferred, for illustrative purposes but the scope of the invention is defined by the appended claims rather than by the foregoing description.

What I claim is—

1. A burner, comprising, a body, a cap, a plurality of plates between the cap and body and means to clamp the body, cap and plates together, the body having inlets for fuel and an atomizing fluid and the plates having transverse passages therethrough to communicate with said inlets, alternate plates having lateral recesses leading from said passages to the edges of the plates.

2. A burner, comprising, a body, a cap, and a plurality of removable plates clamped between the cap and body, an inlet for fuel and an inlet for atomizing fluid both provided in the body and leading to said plates, said plates having communicating transverse passages therethrough to connect with the fuel inlet and communicating transverse passages therethrough to communicate with the other inlet, at least one of the plates having a lateral passage leading from the transverse fuel passage therein to one edge thereof, and at least one of the plates having a lateral passage leading from the other transverse passage therein to one edge thereof.

3. In a burner, two members, and a series of stacked plates clamped therebetween, communicating transverse passages through the plates to conduct fuel, communicating transverse passages through the plates to conduct an atomizing fluid, means connecting with one series of transverse passages and adapted for connection to a fuel supply, means connecting with the other series of transverse passages and adapted for connection to a supply of atomizing fluid, at least one of the plates having a lateral recess leading from the transverse fuel passage therein to an edge thereof, at least one other plate having a similar recess leading from the transverse passage therein

for atomizing fluid, and at least one other plate between the last named plates having only the said transverse passages.

4. In a burner, having two members between which one or more removable plates are adapted to be clamped, and two spaced passages in one of said members opening into a face contiguous to one of said plates, devices to locate the plates relatively to one of said members, and reversible plates, each having two spaced openings to receive said devices and two other spaced openings therethrough so located by and relatively to said devices that one communicates with one of said passages and the other with the other passage and so that when the plate is reversed, the first-named opening communicates with the second-named passage and the second-named opening with the first-named passage.

5. In a burner, having two members between which one or more removable plates are adapted to be clamped, and two spaced passages in one of said members opening into a face contiguous to one of said plates, devices to locate the plates relatively to one of said members, and reversible plates each having an opening therethrough so located by and relatively to said devices as to communicate with either one of said passages according to which face is uppermost, and a recess extending from an edge of the plate inwardly and so located by and relatively to said devices that its inner end may communicate with the other passage.

6. In a device of the class described, a removable plate having two spaced locating openings and two other spaced openings each located equidistantly from the adjacent locating opening, and a recess extending from one of the second named openings to an edge of the plate and terminating at a point equidistant from each of said devices and each of said second-named passages.

7. A burner comprising a body having a pair of spaced passages formed therein, a cap, and a plurality of plates secured between said body and cap, certain of said plates having each an angular slot formed therein and extending inwardly from one edge thereof and so formed as to be capable of communication with one or the other of said passages by reversing the position of the plate.

8. A burner comprising a body having a pair of spaced passages formed therein, a cap, and a plurality of plates secured between said body and cap, certain of said plates having each an angular slot formed therein and extending inwardly from one edge thereof and so formed as to be capable of communication with one or the other of said passages by reversing the position of the plates, others of said plates being inter-

posed between adjacent first-named plates whereby the angular passages formed therein are separated from each other.

9. A burner comprising a body provided with a pair of spaced passages, a cap, a plurality of plates between the body and cap, certain of said plates being provided with angular slots extending inwardly from one edge thereof, and means for securing said plates to the cap and body whereby the slots in alternate slotted plates will easily communicate with one of said passages.
10. A burner comprising a body provided

with a pair of spaced passages, a cap, a plurality of plates between the body and cap, certain of said plates having spaced passages formed therein corresponding with the spaced passages formed in the body, and the remaining plates having slots extending from one edge thereof in position to communicate with one of said passages, the last-named plates being arranged in alternation with the first-named plates and being so positioned that the slots in alternate slotted plates communicate with different passages in the body.

HANNIBAL ALEXANDER KUNITZ.
